(57) **CLAIM**

The ornamental design for an indirect LED light for suspended ceiling, as shown and described.

DESCRIPTION

FIG. 1 is a perspective view from below of an indirect LED light for suspended ceiling;

FIG. 2 is a perspective view from above of the indirect LED light for suspended ceiling;

FIG. 3 is an end elevation full sectional view of that which is shown in FIG. 1 and taken along line 3-3 of FIG. 5;

FIG. 4 is a left end elevation view of that which is shown in FIG. 1, the right end being a mirror image;

FIG. 5 is a front elevation view of that which is shown in FIG. 1, the rear being a mirror image;

FIG. 6 is a top plan view of that which is shown in FIG. 1; FIG. 7 is a bottom plan view of that which is shown in FIG. 1;

FIG. 8 is a perspective view from below of that which is shown in FIG. 1, installed in a ceiling; and,

FIG. 9 is an end elevation view of that which is shown in FIG. 1, installed in a ceiling and depicting how light shines therefrom.

The broken lines in the drawings illustrate portions of the indirect LED Light for suspended ceiling which form no part of the claimed design.

The break lines in the drawings indicate that the appearance of any portion of the indirect LED Light for suspended ceiling between the break lines forms no part of the claimed design.

1 Claim, 6 Drawing Sheets
